UNITED STATES PATENT OFFICE.

LAWSON McCASKY, OF BUTTE, MONTANA.

MINER'S CAP.

1,223,991.

Specification of Letters Patent. Patented Apr. 24, 1917.

Application filed December 5, 1916. Serial No. 135,246.

To all whom it may concern:

Be it known that I, LAWSON McCASKY, a citizen of the United States, residing at Butte, in the county of Silverbow and State 5 of Montana, have invented new and useful Improvements in Miners' Caps, of which the following is a specification.

The present invention contemplates the provision of an attachment for miners' caps, 10 comprehending more particularly a lamp supporting bracket, the object of the invention being to provide a simple, inexpensive and effective device for use upon caps of this character and effectively preventing the 15 transmission of current to the wearer's body.

Furthermore, it is my object to provide a cap of the above stated character wherein a backing is associated with the bracket proper on which the lamp is suspended and having 20 an improved construction of reinforcement so bent to form a brace or truss, thus preventing the weight of the lamp from breaking the backing at the point of formation of the tongue with the body portion of said 25 backing plate.

With the above and other objects in view, the invention consists in the novel features, details of construction and combination of parts which will hereinafter be more fully 30 set forth, illustrated in the accompanying drawing and pointed out in the appended claim.

Figure 1 is a perspective view of a cap showing my attachment assembled therewith 35 and supporting the usual type of miner's lamp thereon;

Fig. 2 is a vertical section taken through the bracket; and

Fig. 3 is a detail perspective view of the 40 backing clearly illustrating the reinforcing means attached thereto.

With reference to the accompanying drawing, in which like characters of reference refer to corresponding parts in the several views, 5 denotes a miner's cap, having secured thereto and disposed in spaced relation with the front portion 6 of said cap a lamp bracket, designated generally by the reference character 7. The salient feature 45 of this invention and the manner in which the lamp bracket is associated with the plate, is to avoid the possibility of short circuiting or injuring the miner by making contact of the metallic portions of the bracket or lamp with current conducting wires, in- 55 stalled in the roof of mines.

To this end, the said bracket 7 consists of identically constructed sections including a backing plate 8 and a supporting plate 9, and as shown the supporting plate is disposed forwardly of and in spaced relation with the body portion 10 of the backing plate 8, when the bracket is applied to the cap. For the purpose of illustration, I have shown the backing plate 8 bent terminally 60 to provide an upper angularly arranged lip 11 and a lower lip 12; whereas the supporting plate 9 is bent at right angles to the body portion 13 thereof to provide the same with an upper angularly arranged tongue 14 and 65 formed at its other end with a lower tongue portion 15.

The bracket as an entirety in order to accomplish the function of preventing transmission of current to the miner's body, is 70 preferably made entirely of stiff fiber board or other insulating material and the tongue portion 14 of the supporting member overlies the lip 11 of the backing plate and 75 is fixedly secured to the peak of the cap, 80 while the lower tongue 15 of the supporting member overlies the lower lip 12 of the backing plate. Arranged upon the outer face of the body portion 13 of the supporting plate 9 is a spring clip 16 for holding 85 on the bracket 7 the miner's lamp 17, and when the lamp is properly positioned in the clip, the same is supported therein by the engagement of the spur of the lamp within the opening 18 of an L-shaped clip 19. This 90 L-shaped clip is terminally engaged at one end and fixed to the upper tongue 14 of the supporting plate, while the opposite end or the vertical portion of the latter mentioned clip is fixed to the front face of the body 95 portion at the point of intersection of the upper tongue 14 with the body portion 13, this when the lamp is supported upon the bracket, will cause the breaking or bending of the supporting member, providing no 100 provisions were made for preventing such. I therefore secure to the opposite longitudinal edges of the body portion and the lower lip 12 of the supporting plate 10, housings 105 having inserted therein spaced parallel reinforcing rods 21, the reinforcing rods 21 being of greater length than the housings 20 to provide the same with protrud-

ing extremities 22. Secured to the opposite longitudinal edges of the upper tongue portion 14 at a point substantially medially of its length, and in alinement with the housings 20 are sleeves 23. The protruding extremities 22 of the reinforcing rods are bent to assume an upward and rearward inclined position, to provide spaced parallel inclined braces 24, terminating in straight shanks 25, 5 the shanks 25 of said braces being inserted in the sleeves 23, thus holding the braces to opposite sides of the supporting member 10 at the point of intersection of the upper tongue portion 14 with the body portion 13, 10 and as before stated, when the weight of the lamp is brought to bear upon the supporting member 10, these braces will prevent any accidental sagging or breaking of the tongue from the body portion, prolonging the life 15 of the bracket, and further preventing any accidental contact of the metallic members of the lamp or bracket in order that a circuit may be completed, thus resulting in the transmission of current to the body of the 20 25 party wearing the cap.

From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I 30

desire to have it understood that the device 35 shown is merely illustrative, and that such changes may be made when desired as are within the scope of the appended claim.

What is claimed as new, is:—

A bracket for supporting miners' lamps 40 upon caps comprising a backing plate and a supporting plate, said plates being terminally bent to provide the same with an upper tongue and a lower tongue, the said supporting plate having its intermediate 45 portion in spaced relation with respect to the backing plate, lamp supporting means upon said supporting plate at the point of formation of the upper tongue portion with said supporting plate, and reinforcing rods 50 attached to the opposite longitudinal edges of the supporting plate, said reinforcing rods being extended beyond the plane of the upper tongue portion, the extending extremities of said rods being bent to provide braces, 55 said braces lying on opposite sides of the point of formation of the upper tongue portion with the supporting plate, sleeves formed on the opposite longitudinal edges of the upper tongue of the supporting plate, 60 shanks formed on the braces adapted to engage the said sleeves for preventing any accidental sagging or breaking of the supporting plate, substantially as and for the purpose specified.

In testimony whereof I affix my signature.

LAWSON McCASKY.
